UNITED STATES PATENT OFFICE.

GEORGE H. CORLISS, OF PROVIDENCE, RHODE ISLAND.

IMPROVED SURFACE-CONDENSER.

Specification forming part of Letters Patent No. 36,280, dated August 26, 1862.

To all whom it may concern:

Be it known that I, GEORGE H. CORLISS, of Providence, in the State of Rhode Island, have invented a new and useful Improvement in Surface-Condensers; and I do hereby declare that the following is a full and exact description thereof, reference being had to the accompanying drawings, in which—

Figure 1 represents a vertical section of the apparatus; Fig. 2, a horizontal projection or ground plan of the same. Figs. 3 and 4 show the form of the upper ends of the tubes employed.

The purpose of my invention is to obtain pure water from the condensation of steam more satisfactorily than has heretofore been done rather than to avoid the effect of atmospheric pressure on the working of the steam-engine.

To enable others skilled in the art to make and use my invention, I will proceed to describe its construction and operation.

A receiver of the steam to be condensed extending over the whole of the ground plan is shown at A, Fig. 1. This is made of sufficient depth to allow room for a workman to operate the apparatus by which the lower ends of the tubes are made water-tight. Tubes which serve as condensing-chambers are shown at B B. These are each connected with the receiver by a water-tight joint.

A case for inclosing these tubes is shown at C C. The tubes B B, which are otherwise cylindrical, are flattened at their upper extremities, as shown in Figs. 3 and 4, in order to form a contracted aperture for restricting the exit of the air or vapor from within the tubes, so that the steam entering from the receiver shall be prevented from passing through the tubes too rapidly for insuring perfect condensation. The upper ends of the tubes are held in position by a diaphragm-plate, D, without being attached thereto.

The heat evolved by the process of condensation may be removed from the exterior surfaces of the tubes by a current of dry or moist air, or by water. In the present instance the apparatus is arranged for the use of water, which enters by the pipe E, and after passing the entire length of the apparatus above the diaphragm D descends through an opening, H, and is returned to the pipe E, through which it flows off freely at a level sufficiently below the upper extremities of the tubes to prevent overflowing them. The water produced by the condensation of the steam is drawn off by a pipe, G, attached to the bottom of the receiver.

It is obvious from the above description that the slight resistance presented by the escaping air through the contracted ends of the tubes tends to an equal distribution of the steam throughout all the tubes.

It will also be seen that the tubes are each free to expand and contract under all changes of temperature without detriment to the apparatus; and it will be further seen that any tube of the whole series may be readily removed without disturbing the others, and that the only joint by which it is attached to the apparatus is conveniently reached by removing the plate I and entering the receiver.

What I claim as my invention, and desire to secure by Letters Patent, is—

1. Constructing the tubes or condensing-chambers of surface-condensers with restricted apertures, substantially as described, and for the purpose specified.

2. The combination of a receiver, A, with a series of tubes, B B, or their equivalents, each of which connects at one extremity with said receiver and at the other with the open air, substantially as described.

GEO. H. CORLISS.
